Primary Examiner — Sandra S Snapp(74) *Attorney, Agent, or Firm* — Greer, Burns & Crain, Ltd.(57) **CLAIM**

The ornamental design for a massager housing, as shown and described.

DESCRIPTION

FIG. 1 is a top perspective view of the present massager housing;

FIG. 2 is a left side view of same;

FIG. 3 is a right side view of the massager housing of FIG. 1;

FIG. 4 is a front view of same;

FIG. 5 is a rear view of the massager housing of FIG. 1;

FIG. 6 is a top plan view of same; and,

FIG. 7 is a bottom plan view of the massager housing of FIG. 1.

The broken line disclosures of the lower housing portion, massager element, cord and cord protector illustrate the environment. None of the broken lines forms part of the claimed design.
